UNITED STATES PATENT OFFICE.

ALENZA T. GIFFORD, OF HOPEDALE, MASSACHUSETTS, ASSIGNOR TO THE
DUTCHER TEMPLE COMPANY, OF SAME PLACE.

AUTOMATIC SPRINKLER.

SPECIFICATION forming part of Letters Patent No. 435,998, dated September 9, 1890.

Application filed March 27, 1888. Serial No. 268,603. (No model.)

To all whom it may concern:

Be it known that I, ALENZA T. GIFFORD, of Hopedale, county of Worcester, State of Massachusetts, have invented an Improvement in 5 Automatic Sprinklers, of which the following description, in connection with the accompanying drawings, is a specification, like letters on the drawings representing like parts.

This invention relates to automatic sprinklers, substantially such as shown and described in another application, Serial No. 243,709, filed by me July 8, 1887, wherein a valve controlling the outlet or discharge opening of a pipe has its valve-stem connected to 15 a reservoir or receptacle containing a volatile medium—such as a hydrocarbon—the said valve being lifted from its seat to permit the discharge of water or other fluid from the pipe when the temperature in the locality in which 20 the sprinkler is placed has reached a predetermined point at which the medium in the reservoir or receptacle is volatilized.

My present invention has for one of its objects to obtain at the valve-opening a head 25 or pressure of water substantially equal to the full head of water in the supply-pipe, so that when the said valve is open the water discharged therefrom will strike upon the distributer-plate of the sprinkler with such 30 force as to be thrown therefrom a considerable distance, thus rendering the said sprinkler effective to protect a substantially large area, as in a mill or other building. This feature of my invention I accomplish by providing a chamber above the valve-seat, and 35 into which the valve is extended, the area of the space between the valve and inner wall of the chamber being equal to or greater than the valve-opening, so that when the valve is raised the water will be free to flow unrestricted through the valve-opening at full 40 head or normal pressure of the water in the supply-pipe, the said chamber being preferably formed in an independent casting or fitting secured to the outlet-pipe and having the 45 sprinkler attached to it, as will be described, or the chamber may be a part of the branch pipe.

Another feature of my invention consists 50 in a distributer-plate, as will be described, by

which the water is more effectually broken up or sprayed.

Other features in which my invention consists will be pointed out in the claims at the end of this specification.

55

Figure 1 in section and elevation shows a sufficient portion of a pipe provided with my improved sprinkler to enable my invention to be understood, the shield or guard for the reservoir being broken out; Fig. 2, a top or 60 plan view of my improved distributer-plate, and Fig. 3 a side elevation of the plate shown in Fig. 2.

The threaded sleeve *a*, having depending legs *a'* inserted in holes in a distributer-plate 65 *a²*, resting upon arms *a³* of a spider *a⁴*, fitted upon a threaded spindle *a⁵*, secured to the under side of a reservoir or receptacle *a⁶*, having screwed or otherwise attached to its upper side the stem *a⁷* of a valve *a⁸* loosely 70 fitted thereon, is substantially as in the application referred to, the top of the distributer being, however, differently shaped, for a purpose to be described. The threaded sleeve *a* has screwed upon it, as shown, a casting or 75 fitting having an annular enlargement, as *b'*, to form a chamber *b²*, into which the valve *a⁸* projects, the bottom of the chamber *b²* being herein shown substantially flush with the top of the threaded sleeve *a*, which forms the seat 80 for the valve. The casting or fitting herein shown has a threaded extension *b³*, preferably screwed into the threaded end of a pipe *b⁴*, which in practice will be a branch pipe of a main or supply pipe. (Not herein shown.) 85

In operation the valve is raised from its seat by the expansion or bulging out of the upper side of the reservoir *a⁶*, due to the volatilization of the hydrocarbon or other medium therein—such as alcohol, &c.—by the 90 heat generated by a fire breaking out in the locality in which the sprinkler is placed. When the valve has been raised from its seat—as, for instance, into the position shown by dotted lines—the water in the chamber *b²* 95 and pipe *b⁴* is forced through the valve-opening at the normal or full pressure of the water in the supply-pipe, the area of the space between the valve and inner wall of the chamber being sufficiently great to permit 100

the water to be charged upon the distributor-plate a^2 under full pressure. The distributor-plate a^2 is concaved from its center toward the circumference or periphery thereof to a point substantially near the center of a radius, as at c , and from this point the plate is inclined downward to a point sub-midway between the point c and the periphery at c' , an annular rim or flange c^2 being formed at this point.

The distributor-plate a^2 normally supports an auxiliary distributor, shown as a corrugated sheet-metal ring c^3 large enough to be readily slipped over the threaded sleeve a , but of smaller diameter than the enlargement b' of the fitting or casting, the said auxiliary distributor being thus free to be raised from the plate a^2 by the force of the water. The corrugations c^4 of the auxiliary distributor are preferably made at an angle to a radial line of the distributor-plate a^2 , so that when the water is forced out radially the edges of the corrugated ring will more minutely divide the said water, thus producing a very fine spray. The corrugations will preferably be beveled at their outer ends, as at $c^5 c^6$, to cause the water to be shot or guided upward at different angles, the bevel c^5 , as shown, being steeper than the bevel c^6 . As the water strikes against the bevels of the corrugated ring, rotation is thus imparted to the said ring, which tends to more effectually spray the water. The corrugated ring is also raised from the distributor-plate a^2 by the water passing under the corrugations c^4 , and some of the water which passes under the said corrugations is projected upwardly by the concave shape of the said plate, while some strikes against the rim or flange, thus creating a spray which is carried away from the sprinkler by the water deflected by the auxiliary distributor. By means of the distributor-plate and auxiliary distributor herein shown, a larger area may be wet and thereby protected than by distributors as heretofore constructed and known to me. The valve will be maintained open by a clutch-ring d , resting on an arm d' on the under side of the distributor-plate, and the reservoir may be protected from the cooling effect of the water by the shield d^2 , as in the application referred to.

The reservoir a^6 will preferably be made as herein shown, its bottom being rigid or of such strength as not to be bulged out or distorted by the volatilization of the hydrocarbon or other medium, the latter acting only on the upper or flexible part of the reservoir, thereby causing the valve to be moved from its seat very quickly and at a minimum expansion of the volatile medium.

I have herein shown the chamber b^2 as formed by an independent casting; but I do not desire to limit my invention to this particular construction, as the branch pipe itself

may be made of sufficient size with relation to the threaded nozzle a to obtain the desired area or space between the valve and inner wall of said pipe.

I claim—

1. In an automatic sprinkler, a distributor-plate and valve-seat and a valve fitted thereon, combined with a chamber into which the said valve is extended, said chamber between the valve and its inner wall being of an area substantially equal to or greater than the valve-opening, and with an auxiliary distributor composed of a corrugated ring, substantially as described. 70

2. In an automatic sprinkler, a distributor-plate, a valve-seat and a valve fitted thereon, and a reservoir to contain a volatile medium and connected to said valve, combined with an auxiliary distributor composed of a corrugated ring, substantially as described. 75 80

3. In an automatic sprinkler, a distributor-plate having its upper face concaved and provided with a rim or flange, as c^2 , a threaded sleeve supported thereby and constituting a valve-seat, a reservoir to contain a volatile medium, a valve-stem connected thereto, and a valve mounted on said stem, combined with a casting or fitting having an enlargement, as b' , to form a chamber b^2 , substantially as and for the purpose specified. 85 90

4. In an automatic sprinkler, a distributor-plate, a valve-seat and a valve fitted thereon, and a reservoir to contain a volatile medium and connected to said valve, combined with an auxiliary distributor composed of a corrugated ring having beveled sides $c^5 c^6$, substantially as described. 95 100

5. In an automatic sprinkler, a distributor-plate, a valve-seat and a valve fitted thereon, and a reservoir to contain a volatile medium and connected to said valve, combined with an auxiliary distributor composed of a ring having corrugations inclined with relation to the radii of the distributor-plate, whereby rotation is imparted to the said ring by the water or other fluid discharged from the sprinkler, substantially as described. 105 110

6. In an automatic sprinkler, a distributor-plate and valve-seat and a valve fitted thereon, combined with a chamber into which the said valve is extended, said chamber between the valve and its inner wall being of an area substantially equal to or greater than the valve-opening, and with a corrugated ring forming a movable and rotatable auxiliary distributor normally supported by the distributor-plate, substantially as described. 115 120

In testimony whereof I have signed my name to this specification in the presence of two subscribing witnesses.

ALENZA T. GIFFORD.
